United States Patent Office.

CONSTANT S. ROUSE, OF DOWAGIAC, MICHIGAN.

Letters Patent No. 83,795, dated November 3, 1868.

IMPROVED STEP-LADDER.

The Schedule referred to in these Letters Patent and making part of the same.

To all whom it may concern:

Be it known that I, CONSTANT S. ROUSE, of Dowagiac, in the county of Cass, and State of Michigan, have invented a new and improved Method of Bracing Fruit-Ladders, whereby they are prevented from slipping at the bottom, and are readily converted into extension-ladders, for going up on to high buildings; and I do hereby declare that the following is a full and exact description thereof, reference being had to the accompanying drawings, and to the letters of reference marked thereon, in which—

Figure 1 is a perspective view of the ladder when used for gathering fruit and the like purposes, and

Figure 2 is a detached longitudinal section, showing the position of the braces, and the manner of fastening them, when used as an extension-ladder.

The nature of my invention relates to that class of fruit-ladders which are constructed by pivoting two ladders, by their top rounds, to opposite sides of a platform, and bracing the same from hangers, attached to the under side of the platform; and consists in attaching the braces to a thick guide-block, which slides up and down on the hanger, having corresponding holes in the block and hanger, to receive a pin, for the purpose of fastening and holding the ladders from slipping, and for permanently fastening the ladders when extended to their full length.

To enable others skilled in the arts to make and use my invention, I will proceed to describe its use and construction.

A A are two ladders, with rounds of the usual construction.

B is the platform.

C C are the hangers or legs to the platform.

D D are the blocks or guide, to which the braces F are pivoted by the rounds E E.

The holes r r r are to receive the pin H, for the purpose of fastening the blocks immovably on the hangers.

The guide-blocks D D have a mortise through the centre, to receive the hangers C C.

Thus it will be seen that by means of the holes r r r and the pin H, the block D D can be fastened at any elevation of the platform desired, and secured against the possibility of slipping, and, when the ladders are extended to their full length, the pin H may be inserted in the upper hole, r, making one continuous ladder of A A, of great strength and convenience.

Having thus described my invention,

What I claim as new, and desire to secure by Letters Patent, is—

The guide-blocks D D, the pin H, and rounds E E, when combined with the platform-braces and ladders, as and for the purposes set forth.

In witness that I claim the foregoing, I have hereunto set my hand, this 3d day of September, 1868.

CONSTANT S. ROUSE.
